POLICE CLUB OR SIMILAR ARTICLE

Paul D. Starrett, Rindge, N.H., assignor to Monadnock
Lifetime Products, Inc., Fitzwilliam, N.H.

Filed Feb. 1, 1973, Ser. No. 328,666

Term of patent 14 years

Int. Cl. D22—02

U.S. Cl. D22—99

FIG. 1

FIG. 2

FIG. 4

FIG. 1 is a top view showing one end of the police club or similar article according to my new design;

FIG. 2 is a front view;

FIG. 3 is a side view with both sides being identical; and

FIG. 4 is a back view.

The design has been shown broken away for convenience of illustration.

I claim:

The ornamental design for a police club or similar article, as shown and described.
